UNITED STATES PATENT OFFICE.

JOSEPH M. EDGAR, OF KANSAS CITY, MISSOURI, ASSIGNOR TO JOHN Z. RORABACK, OF SAME PLACE.

INDICATOR-LOCK.

SPECIFICATION forming part of Letters Patent No. 449,314, dated March 31, 1891.

Application filed September 13, 1890. Serial No. 364,875. (Model.)

To all whom it may concern:

Be it known that I, JOSEPH M. EDGAR, a citizen of the United States, residing at Kansas City, in the county of Jackson and State 5 of Missouri, have invented a new and useful Improvement in Indicator-Locks, of which the following is a specification.

My invention relates to an improvement in the class of permutation-locks known as "indicator-locks."

My object is to provide a comparatively simple and highly effective construction of indicator-lock, the principle involved in which shall be adaptable for use for the purposes, 15 generally, to which permutation-locks are applicable, but which construction shall be especially useful in connections wherein the service desired of the lock is not so much that of precluding the opening thereof as to indicate the fact that such opening has been attempted or accomplished. Locks in this sense of various descriptions have been hitherto provided for especial use on the doors of freight-cars and the like; and my improvement 20 is particularly designed for use in that connection.

In the accompanying drawings, Figure 1 is a view in elevation of a lock involving my improvement and constructed in the form of 30 a padlock; Fig. 2, a vertical section through the device as shown in Fig. 1; Fig. 3, a section taken on the line 3 of Fig. 2 and viewed in the direction of the arrow. Fig. 4, a section taken on the line 4 4 of Fig. 1 and 35 viewed in the direction of the arrows; and Figs. 5, 6, 7, and 8 are plan views of details of the indicator mechanism.

A is a case containing any desired number, more than one, of rings having teeth provided around their inner circumferences, differing in number on the respective rings and supported concentrically one above the other (regarding the lock as used in a vertical position) and preferably out of contact with 40 each other inside the case. The case contains, furthermore, a pinion for each ring, supported eccentrically inside the series of rings to engage their teeth and accessible from without the case to enable rotation 45 thereof and thereby effect rotation of the rings. Each ring is provided about its exterior

55

nal circumference with characters, as numbers or letters, or both, as shown, which should coincide with the internal teeth, whereby turning of the rings will bring combinations of the characters in vertical series to a transparent (as a glass-covered) vertical opening *r* in the case.

50

The foregoing is a general description of my improvement, stating what are considered the essential features of the construction in any form of the lock.

A detailed description of the lock as it is illustrated in the drawings in a padlock form and involving the preferred construction of 65 the details is as follows: The case A tapers toward its base and has hinged to one side of its flaring end a bolt B, formed into a catch *q* at its free end and there adapted to enter a recess *p* in a protuberance *p'* opposite that 70 at which the bolt is hinged to the case. The flange *o* at the end of the recess *o'* of the catch *q* in the end of the bolt projects, when the catch is inserted into its recess *p*, beyond the inner surface of the case, as shown in 75 Fig. 2. In the base *n* of the case A an opening *n'* is provided eccentrically, and the vertical glass-covered opening *r* is provided in a side of the case A. The interior of the case is provided circumferentially with shoulders *m*, 80 *l*, and *k*, the number of which may, however, be less or more than three, depending on the number of rings, hereinafter described, to rest upon them, and for which they afford seats. Above the uppermost seat *k* a shoulder *i* is provided to afford a guide-seat for a horizontal circumferential flange around the upper edge of the uppermost ring.

90

95

D, E, F, and G denote the rings hereinbefore referred to. Each is in the form of an annular band having teeth *t* projecting toward its center at intervals around its interior surface and preferably from near the upper edge of the ring, as shown, and around the outer surface of each band are provided characters, as the numerals and letters shown, which should respectively correspond in number and coincide with the teeth *t* on each. The lowermost internal gear-ring D, provided with a certain number of teeth *t*—say eleven, as shown—fits with desirable looseness the lower part of the case A and rests on its base *n*.

The next ring E is of greater diameter than the ring D to rest in the seat m, and has an increased number of teeth t—say twelve, as shown. The ring F is of still greater diameter to adapt it to rest on the seat l, and has more teeth than the ring E—say thirteen, as shown—and the ring G, having the largest number of teeth t—say fourteen—is of a diameter to adapt it to rest on the seat k. Around its upper edge the uppermost internal gear-ring has a horizontal notched flange h, the notches h' in which may be provided in any desired number and, if several be provided, as shown, at equal or unequal intervals. Each notch must be sufficiently wide to admit the catch end q of the bolt, which is locked against withdrawal from the recess p by turning the uppermost ring (which is, as will thus be seen, in the nature of an annular tumbler) to cause its flange h to overlap the flange o of the catch q.

While it is preferred that the rings shall rest on seats and differ in their diameters, as described, they may rest one upon the other and be all of the same diameter, provided they vary as to the number of their teeth t, though the variation in the number of the teeth need not be in the order shown, but may be inversely of that order or in different or irregular order.

C is a rotary pinion-shaft terminating at its lower end in a slotted head g, fitting the opening n' provided eccentrically in the base n of the case and having its lower bearing 35 against the inner surface of the base n, afforded by a collar f. The upper end of the shaft C has its bearing in the cover A' of the case A. The shaft C is provided radially with teeth t', which may, without impairing 40 it for my purpose, extend each continuously along the length of the shaft within the case. I prefer, however, to form or provide the teeth t' on the shaft C in a manner to produce pinions C' at intervals, one for each ring, 45 to engage with the internal teeth t thereof. As shown, each pinion C' has six teeth and is much smaller in diameter than the interior diameter of any of the internal gear-rings, but meshes with the teeth thereof at one side of 50 each ring by being set in the eccentric bearings for the opposite ends of the pinion-shaft.

The lock is worked by turning the shaft C' on its axis, and I provide for so turning it by adapting the head g to admit a suitable key 55 (not shown) into a slot g', forming a key-seat. Of course any rigid instrument that will enter the slot g' and may be manipulated for turning it will answer the purpose of a key. By turning the shaft C the several pinions C' 60 engage the teeth t of the respective rings D E F G; but, owing to the difference in the number of the internal gear-teeth, the rings, while each is turned by a pinion-tooth, the extent of a tooth t, thus bringing with each such turn 65 a different character to view at the opening r, they are turned differentially, whereby not only a new vertical combination is brought

to the opening r by turning the shaft C the extent of one tooth of each pinion, but, because the production of a complete revolution of 70 the ring having the smallest number of teeth t will produce only partial revolutions of the others, the combination must obviously be changed with each such complete revolution. A spring-dog e or stop (indicated by a dotted representation in Fig. 5) is provided on the under side of the cover A' to engage with the teeth t of the uppermost ring G and prevent its pinion from being turned to reverse it, whereby also, obviously, backward turning 80 of the other rings is prevented.

As I have arranged the characters on the respective rings the one having the fewest teeth is provided with the numbers 0 to 9 in succession and the letter A. That having the 85 next larger number of teeth has the same order of numbers succeeded by the letters A B. The third ring in order as to the increasing number of teeth has the stated order of numbers succeeded by the letters A B C, and the 90 uppermost ring having the largest number of the teeth has the said numbers followed by the letters A B C D. However, the arrangement and nature of the characters for forming the combinations may of course be provided in any other suitable manner. When a notch h' in the flange of the ring G is brought coincident with the catch p on the end of the bolt B the latter may be withdrawn. If but one notch h' is provided, to unlock the 100 bolt requires the uppermost ring to be turned completely around, while if there be several such notches the unlocking may be effected the number of times corresponding with the number of notches in each said revolution. 105 By making a tumbler like the ring G of each or several of the other rings the unlocking could only be effected readily with a knowledge of a particular combination.

When my improved indicator-lock is used 110 for sealing freight-car doors or for any analogous purpose wherein the device is to serve more as a detector than a lock, I cover the opening n' in the base n of the case, and thereby also the head g of the shaft C, with 115 card-board or other permeable material that will necessitate puncturing or cutting to permit access to be had with a key to the key-seat g' and leave evidence of such puncturing or cutting. I show the means referred to, and which thus afford a detector in addition to that afforded by the permutation mechanism, as a card-board disk d, confined in an annular metal holder c, permanently secured to the base n of the case A over the head g of 120 the pinion-shaft. If the lock be of a form wherein in its use the internal gear-rings are caused to extend horizontally or side by side, such arrangement is of course intended to be included in the terms of the appended 125 claims.

What I claim as new, and desire to secure by Letters Patent, is—

1. In an indicator-lock, the combination,

with a suitable case and a bolt, of rings supported one above the other and independently revoluble in the case and provided on their inner sides with teeth t , differing in number 5 on the respective rings, and externally with characters, a pinion for each ring, supported eccentrically within the series of rings in engagement with the teeth t and accessible to permit rotation thereof and thereby produce 10 rotation of the rings from without the case, and means, substantially as described, for locking the bolt, substantially as and for the purpose set forth.

2. In an indicator-lock, the combination of 15 a case A, provided internally with seats arranged one above the other, a bolt, rings supported and independently revoluble on the seats and provided on their inner sides with teeth t , differing in number on the respective rings, and externally with characters, a pinion for each ring supported eccentrically within the series of rings in engagement with the teeth t and accessible to permit rotation thereof and thereby produce rotation 20 of the rings from without the case, and means, substantially as described, for locking the bolt, substantially as and for the purpose set forth.

3. In an indicator-lock, the combination, 25 with a suitable case and a bolt, of rings supported one above the other and independently revoluble in the case and provided on their inner sides with teeth t , differing in number on the respective rings, and externally with characters, a pinion for each ring supported eccentrically within the series of rings in engagement with the teeth t and accessible to permit rotation thereof and thereby produce rotation 30 of the rings from without the case, and means, substantially as described, for locking the bolt, substantially as and for the purpose set forth.

4. In an indicator-lock, the combination, 35 with a case A, having a bolt B, of rings supported one above the other and independently

revoluble in the case and provided on their inner sides with teeth t , differing in number on the respective rings, and externally with characters, the outermost ring forming a tum- 50 bler to engage and lock the bolt, a pinion-shaft C, journaled in the case to extend eccentrically through the rings and having pinions C' engaging the teeth t , and a stop for preventing backward turning of the rings, 55 substantially as and for the purpose set forth.

5. An indicator-lock comprising, in combination, a case A, having a bolt B, rings supported one above the other and independently revoluble in the case and provided on their 60 inner sides with teeth t , differing in number on the respective rings, and externally with characters, the outermost ring having a notched flange h to engage and lock the bolt, a pinion-shaft C, journaled in the case to ex- 65 tend through an end thereof and eccentrically through the rings and having pinions C' en- gaging the teeth t , a key-seat in the exposed said end of the shaft C, and a stop for pre- 70 venting backward turning of the rings, sub- stantially as and for the purpose set forth.

6. An indicator-lock comprising, in combination, a case A, having a bolt B, rings supported one above the other and independently revoluble in the case and provided on their 75 inner sides with teeth t , differing in number on the respective rings and externally with characters, the outermost ring having a notched flange h to engage and lock the bolt, a pinion-shaft C, journaled in the case to ex- 80 tend through one end thereof and eccentrically through the rings and having pinions C' en- gaging the teeth t , a key-seat in the ex- posed said end of the shaft C, a permeable shield d, secured to cover the said key-seat, 85 and a stop for preventing backward turning of the rings, substantially as and for the pur- pose set forth.

JOSEPH M. EDGAR.
